(57) **CLAIM**

The ornamental design for a cat litter box, as shown and described.

DESCRIPTION

FIG. 1 is a front perspective view of a first component of the cat litter box, removed for ease of illustration, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof.

FIG. 9 is a front perspective view of a second component of the cat litter box, removed for ease of illustration;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front perspective view of the cat litter box in a combined state of use; and,

FIG. 18 is a rear perspective view of the cat litter box in a combined state of use.

The broken lines illustrate portions of the cat litter box that form no part of the claimed design.

1 Claim, 18 Drawing Sheets
